CLAIM

I claim the ornamental design for an electric motorcycle, as shown and described.

(30) **Foreign Application Priority Data**

DESCRIPTION

Feb. 2, 2018 (VN) 3-2018-00271

FIG. 1 is a front and right side perspective view of a first embodiment of an electric motorcycle in accordance with the design;

(51) **LOC (13) Cl.** **12-11**

FIG. 2 is a rear and left side perspective view of the design thereof;

(52) **U.S. Cl.**

FIG. 3 is a front view of the design thereof;

USPC **D12/110**

FIG. 4 is a rear view of the design thereof;

(58) **Field of Classification Search**

FIG. 5 is a right side view of the design thereof;

USPC D12/110, 111, 117, 128-133; D21/432,

FIG. 6 is a left side view of the design thereof;

D21/538

FIG. 7 is a top plan view of the design thereof;

CPC B62K 11/00; B62K 11/02; B62K 11/04;

FIG. 8 is an underside plan view of the design thereof;

B62K 11/10; B62K 17/00; B62K 19/00;

FIG. 9 is a front and right side perspective view of a second embodiment of an electric motorcycle in accordance with the design;

(Continued)

FIG. 10 is a rear and left side perspective view of the design thereof;
FIG. 11 is a front view of the design thereof;
FIG. 12 is a rear view of the design thereof;
FIG. 13 is a right side view of the design thereof;
FIG. 14 is a left side view of the design thereof;
FIG. 15 is a top plan view of the design thereof; and,
FIG. 16 is an underside plan view of the design thereof.
The broken lines in the Figures are for environmental purposes only and form no part of the claimed design.
